UNITED STATES PATENT OFFICE

163,332

WALLPAPER OR THE LIKE

James Seeman, Forest Hills, N. Y.

Application May 23, 1950, Serial No. 10,111

Term of patent 14 years

(Cl. D59—10)

To all whom it may concern:

Be it known that I, James Seeman, a citizen of the United States of America, residing in Forest Hills, county of Queens, and State of New York, have invented a new, original, and ornamental Design for a Wallpaper or the like, of which the following is a specification, reference being had to the accompanying drawing, forming part thereof,

Fig. 1 is a face view of a portion of the design unit of the wallpaper.

Fig. 2 is a face view of the remaining portion of the design unit thereof, the whole showing my new design.

I claim:

The ornamental design for a Wallpaper or the like, substantially as shown.

JAMES SEEMAN.
